DYEING MACHINE

Ferdinand C. Neu, Ridgefield, N. J.

Application September 1, 1949, Serial No. 113,521

5 Claims. (Cl. 68—206)

1

This invention relates to dyeing apparatus and in particular to a machine in which a plurality of skeins of material may be dyed.

A particular object of the invention is to so arrange the dye spraying means with respect to the skein holding means, that the material will be thoroughly and effectively saturated by the proper amount of dye to carry out the coloring operation.

In a machine, of the character herein disclosed, where heated dye fluid under pressure is employed, it is an object of the invention to provide for protection of the machine attendant so that he will not be scalded by the vapor or fluid when the machine is opened for any purpose such as removing and replacing the skeins of material.

A further object is to provide means for rotating the skeins as they are subjected to the impingement of the dye fluid so that the strands are supported loosely and separate during the rotating motion of the skein to become thoroughly saturated with the dye fluid.

Other objects of the invention are to provide means for rotating the skeins first in one direction and then in another and to control the rotation automatically so that the material of the skein is contacted by the sprayed fluid from all angles and in a consistent manner whereby the dyeing operation can be closely controlled; to provide safety means for cutting off the flow of dye fluid and stopping the moving parts of the machine automatically when the latter is opened; to provide means for holding the skeins so that the machine can be quickly loaded and emptied; and to arrange for the circulation and heating of the dye fluid in such a manner as to obtain maximum operating efficiency of the machine.

With these and other objects in view, the invention comprises certain construction herein-after described and then particularly pointed out in the claims and a preferred embodiment of my invention is illustrated in the accompanying drawings in which:

Figure 1 is a view in side elevation of a skein dyeing machine constructed in accordance with the invention.

Figure 2 is an enlarged section taken on the line 2—2 of Figure 1 showing the relation of a skein holder to the dye fluid spray means.

Figure 3 is a section taken on the line 3—3 of Figure 1 showing the dye fluid circulating means, 50

2

Figure 4 is a top plan view of the machine with parts broken away to show the interior structure thereof.

Figure 5 is a view in rear elevation with parts of the housing broken away and omitted to show the skein rotating means,

Figure 6 is a view in vertical section taken on the line 6—6 of Figure 5 showing the general structure and arrangement of the parts, and

Figure 7 is a diagram of the electric circuit used in the machine.

Referring to the drawings in detail 10 indicates a frame upon which is mounted a tank 11 which constitutes the dyeing chamber of the machine, 15 the tank being substantially rectangular in shape and presenting bottom, side and end walls 12, 13 and 14 respectively, made of any suitable metal and closed in the front side wall 13 by a door 15 closely fitting within the flanged rim 16 of the door opening in said front wall and hinged adjacent thereto as at 17.

The rear wall 13 (Figure 6), at the upper part thereof supports a shelf 18, the opposite ends of which constitute extensions 19 of the end walls 14 and are shaped to provide journal receptacles 20 through which passes the dye fluid supply pipe 21 and about which is pivotally mounted, with a suitable fluid seal, a hollow cover 22. The latter is provided along its rear edge with a tubular fluid pipe housing 23 of larger diameter than said pipe 21 so that dye fluid coming out of perforations 24 along the back of the pipe 21 will flow therearound and be effectively distributed along the floor 25 of the cover to flow evenly out of the strew holes 26 arranged longitudinally in spaced drip bars 27 positioned in suitable openings extending laterally of the floor 25 of the cover. The rear edge of the floor is flanged as at 28 to coat with the outwardly flared upper edge of the tank to provide a seal. The edges of the cover provide a seal fit with the upper edge of the tank and the front door 15 is prevented from being accidentally opened by a gravity latch 29 pivoted to the handle 30 of the cover 22 and having a pin-in-slot connection 31 with the handle so that the latch automatically prevents the door 15 from being accidentally opened or being forced open. The cover 22 at its rear carries a bailed counterweight 32 so that the operator is assisted in raising the cover. Within the tank, the skeins to be dyed are

mounted on spaced skein carriers 33 which extend across the tank and are each positioned directly beneath a drip bar 27. As many skein carriers as desired may be used depending upon the capacity of the machine. Each carrier consists of a pair of discs 34 connected by rods 35 which are supported in spaced annular arrangement about the axis of the disc. The inner disc is mounted on the end of a drive shaft 36 journaled in the rear wall of the tank and the side walls of a gear box 37 mounted on the shelf 18. The shaft of the carrier at one end of the tank is extended to receive a drive gear 38 (Figure 5) driven through a pinion 39 from a motor 40. Each of the shafts 36 carries within the gear box 37 a chain sprocket wheel 41 for driving engagement with an endless sprocket chain 42 passing over idlers 43, one of which is mounted in a lever 44 for automatic tensioning of the chain by a coil spring 45, the tensioned position of the idler being insured by an adjusting stop screw 46 in the end wall of the gear housing. The motor 40 is reversed in its action at predetermined time intervals under control of a timer 47 and a reversing switch 48 connected in circuit. The reversal of the motor causes the skein holders 33 to rotate clockwise and counter-clockwise a predetermined number of revolutions and the annular spacing of the rods 35 gently rotates the skeins so that all parts thereof will be subjected to the action not only of the dye coming through the strew holes 26 but through the opposite lines of spray holes 49 in a spray pipe 50 extending parallel to each skein carrier and close enough to the latter so that the skeins hang loosely about the pipe and are maintained in this relation by the spacing of the carrier rods. The pipe 50 is supported in the side wall of a dye distributing manifold 51, having a constricted portion 52 and a lower chambered portion 53, and passes through the rear side wall of the tank to terminate in a capped end adjacent the front side wall thereof.

The dye fluid under pressure is circulated through pipes 54 connecting opposite ends of the manifold with opposite ends of the pipe 21 which passes through the cover 22 and through the spray pipes 58 to be forced through the drip bar and spray pipe openings into the tank to bathe the skeins and be caught in the bottom of the tank and drawn (Figure 3) through a screen 55 into a sump 56, through pipe 57, and a pump 58 driven by a motor 59. From the outlet side of the pump 58 the fluid passes through a control valve 60 into a pipe 61 entering the chambered lower part 53 of the manifold 51 and also through a pipe 62 to a distributing nozzle 63 mounted in an end wall 14 of the tank. The nozzle consists of divergent tubes 64 of reduced diameter with respect to the pipe 62 and slotted in the crotch or bifurcation thereof as at 65 so that openings are provided for the ejection of three streams of dye that agitate the dye in the bottom of the tank to prevent sediment from settling.

A discharge valve 66 beyond pipe 62 may be used to empty the machine through a pipe 67. The motor 59 as well as motor 40 are automatically controlled for the safety of the machine attendant by providing in a common circuit, not shown, a control switch 68 having a roller arm 69 for engagement with the side of the counter-weight bail or cover so that as the latter is initially raised, the roller rides free and automatically breaks the circuit to both motors. Consequently any attempt to open the front door 15 will necessitate raising the cover 22 and this will

4 automatically shut off the pump operation, and the movement of the skein carriers.

While the valves 60 and 66 are shown in conventional manner, the operating handles thereof can be extended through suitable levers and links so that they can be controlled from a point adjacent the front of the machine.

The dye fluid is maintained in heated condition by the introduction of steam through a U-shaped or other conveniently arranged steam inlet pipe 70 having perforations so that the steam can escape directly into the fluid adjacent the bottom of the tank. The flow of the steam may be controlled in any well known manner.

15 In the operation of the machine, the skeins are placed along each carrier and the cover closed so that circulation of the dye fluid takes place and reversal of rotation of the skeins during the dyeing process. The projecting carriers facilitate 20 loading and removal of the skeins and the relative arrangement of the dye vents effectively and thoroughly dye the material of the skeins in the shortest time.

The timer 47 is of standard make and can be 25 adjusted for varying time intervals and in view of the fact that both the timer and the reversing switch are well known products and are not claimed per se herein, it is not believed that further illustration is needed.

30 My invention is not to be restricted to the precise details of construction shown since various changes and modifications may be made therein without departing from the scope of the invention or sacrificing the advantages to be 35 derived from its use.

What I claim is:

1. A machine for dyeing material comprising a tank, rotatable carriers for supporting skeins of the material mounted in said tank, a cover 40 for the tank, comprising a hollow housing presenting a lower wall, perforated drip bars in said wall, a perforated fluid pipe passing through said housing and constituting a pivot about which the cover can be swung and a section of the housing encasing said pipe being spaced therefrom in a portion adjacent the perforations to provide for evenly distributing the fluid over the lower wall of said cover, a plurality of means for spraying dye fluid on said skeins, means for 45 circulating the fluid through the tank, the cover and said spraying means, and means regulated by the opening and closing movements of said cover for respectively stopping and starting the operation of said fluid circulating means for 50 controlling the circulation of the fluid.

55 2. A machine for dyeing material as set forth in claim 1 in which one of said fluid spraying means comprises a plurality of perforated pipes extending into said tank, and said drip bars and 60 said pipes being disposed in vertical alignment with and in opposing relation to said skein carriers.

65 3. A machine for dyeing material as set forth in claim 1 in which the fluid circulating means includes a motor operated pump, a circuit including said motor and a switch and an arm on the switch movable by the opening and closing movements of said cover to make and break said circuit.

70 4. A machine for dyeing material as set forth in claim 1 including means for rotating said carriers including shafts for mounting the carriers and sprockets on said shafts, a drive chain common to all of said sprockets, means for driving said chain including a motor and a drive

gear, and means for automatically reversing the operation of said motor at time intervals.

5. In a machine for dyeing material as set forth in claim 1 including, a nozzle projecting into said tank at one side thereof said nozzle terminating in divergent tubular portions and a perforated crotch portion between said portions for directing a plurality of separate streams of fluid across the tank.
